Primary Examiner—Alan P. Douglas*Assistant Examiner*—Robin V. Taylor[57] CLAIM

The ornamental design for a clothes pin box, as shown and described herein.

DESCRIPTION

FIG. 1 is a perspective of a clothes pin box, showing my new design, the lid part being closed;

FIG. 2 is a rear view thereof, the lid being closed; and,

FIG. 3 is a side view thereof, the lid being closed.

The broken line showing is for illustrative purposes only and forms no part of the claimed design.
